UNITED STATES PATENT OFFICE.

CHARLES LIONEL MARCUS, OF NEW YORK, N. Y.

DESIGN FOR AN ATOMIZER.

Application filed September 23, 1927. Serial No. 23,531. Term of patent 14 years.

To all whom it may concern:

Be it known that CHARLES LIONEL MARCUS, a citizen of the United States, and resident of New York city, in the county of New York and State of New York, has invented a new, original, and ornamental Design for Atomizers, of which the following is a specification, reference being had to the accompanying drawing, forming part thereof, in which—

Fig. 1 is an elevational view of an atomizer embodying my new design; and

Fig. 2 is a developed view showing the ornamentation on the body thereof.

I claim:

The ornamental design for an atomizer as shown, and described.

Dated New York city, September 21, 1927.

CHARLES LIONEL MARCUS.
